UNITED STATES PATENT OFFICE.

HARVEY W. ROBINSON, OF NEW ORLEANS, LOUISIANA.

CURRENT MOTOR.

Application filed September 29, 1925. Serial No. 59,425.

The prime object of this invention is to provide improvements in a current motor device adapted for the purpose of utilizing the motion and power due to the flow of the water in a river stream, brook or the like.

A further object is to provide a power mechanism consisting of a water wheel on a float adapted to be anchored or otherwise in a running stream so that the water flowing in the stream will rotate a power wheel which in turn may function to drive various appliances.

Another object of this invention is to provide improved means for controlling the force of the current as applied to the water wheel.

Other objects will appear during the following detailed description of the device, and from the two sheets of drawings hereinafter made a part of this application.

In the drawings,

Fig. 1 illustrates the plan view of the current motor device in assembled form.

Fig. 1^a represents a plan view of the bracket for guiding the deflecting plane raising and lowering mechanism.

Fig. 2 illustrates a side elevational view of Fig. 1.

Fig. 3 represents a side elevational view of the current motor device disclosing operations thereof in sections.

Fig. 4 represents a plan view of the forward end of the current motor device showing particularly the deflecting plane in relationship thereto.

Fig. 5 illustrates a forward end elevational view of the current motor device particularly disclosing the deflecting plane in relationship to the device and the means for raising and lowering the plane.

Numerals 1 and 2 designate sections of an ordinary float carrying thereon one or more undershot water wheels 3, 4 and 5, the wheels having blades 6, suitably formed for the purpose of a current motor drive. The float may carry one or more of these water wheels without affecting in any way the merits of this invention.

Suitable standards and journals are attached to the floats as at 7, 8, 9, 10, 11 and 12 for the purpose of receiving the spindles or shafts 13, 14, and 15 on the water wheels. To the spindles or shafts are properly geared the driving elements 16, 17, and 18, adapted to be utilized for mill service or

otherwise. At the forward end of the float a deflecting plate 19 is positioned, the inner end of plate 19 being pivoted or hinged to a section 20, which section is securely fastened to the float at a point underneath the water wheels, the section 20 being preferably of a narrow flat strip of material of suitable width to one edge of which, the inner end of the deflecting plate 19 is pivoted or hinged, the other edge of section 20 being adapted to receive an auxiliary deflecting plate 21 suitably hinged or pivoted thereto and adjustable as required. Deflecting plates 22 and 23 together with the required pivoted sections 24 and 25 are located in their proper relative positions with respect to the water wheels 4 and 5.

Means are provided for raising and lowering the deflecting plates, consisting of suitable mechanism attached as at 26 to the deflecting plate 19 and extending upwardly through a suitable bracket 27 attached to the float portions 1 and 2, and adapted to be lowered or raised as required by means of a crank handle 28, the crank handle and shaft being suitable carried on standards 29, attached in a proper manner to the floats by means of bolts, screws, or otherwise. The crank shaft is adapted to receive a guard 30 having teeth adapted to mesh and cooperate with a ratchet gearing 31, slidably guided in the bracket 27. The forward deflecting plate 19 is preferably formed having a fan shaped forward portion and a rectangular shaped rear portion, the forward edge of the plate being preferably on a line with the extreme forward point or sections of the floats. The deflecting plate for the water wheels in the rear are of rectangular shape, however, as stated above, the number of water wheels included in this device would not affect materially the merits of the invention, the novelty and utility being confined primarily to the features disclosed and described in connection with the forward water wheel 3, and the combination of features thereto, including the deflecting plate 21, together with a suitable means for raising and lowering the deflecting plane.

Loosely attached at the extreme forward points or side edges 32 of the floats, are forwardly extending guards 33 adapted to be securely fastened together at a point 34. These guards 33 may be made of suitable material such as wood or otherwise, and will

function to protect the forward end of the float and deflecting plate from damage due to driftwood or otherwise.

At the outer end 34 of the guard, the float 5 35 is preferably attached and suitably arranged, and weighted, so that the outer end of the guard may be partly submerged in order to better protect the float. An anchor cable 36 may be suitably attached to the 10 float at points 37.

In operation this invention provides a current motor device having efficient means for regulating particularly the force of the current applied to the water wheel comprising a deflecting plate 19 formed in one 15 piece, the forward end of which is fan shaped and does not extend beyond the outermost portion of the float.

It has been determined from experiment 20 that the deflecting plate as claimed and described herewith, is of the highest efficiency, adapted as it is to be easily and conveniently lowered and raised as required, by means of a suitable device.

25 In operation the efficiency of the deflect-

ing plate 19, is furthermore greatly increased by its special pivoted connection with the fixed section 20 and the loosely pivoted auxiliary plate 21. These three deflecting elements in combination form a 30 highly satisfactory means for regulating the force of the current applied to the water wheels particularly to the forward wheel.

What I claim is:

In a current motor device comprising a 35 float, an undershot wheel, and current deflecting plates arranged to cooperate with the wheel, one plate extending rearwardly of the wheel and one plate extending forwardly of the wheel, means for pivotably 40 connecting the plates in spaced relationship to the wheel, consisting of a supporting element secured in a suitable location to the float underneath the wheel, the inner edge of both the forward and rear plate being 45 pivoted to the supporting element, and means for raising and lowering the plates.

In testimony whereof I affix my signature.

HARVEY W. ROBINSON.
